UNITED STATES PATENT OFFICE.

STEVE BOROS, OF KENMORE, OHIO.

PAPER-HANGING MACHINE.

Application filed November 6, 1925 Serial No. 67,374.

To all whom it may concern:

Be it known that I, STEVE BOROS, a citizen of the Republic of Hungary, residing at Kenmore, in the county of Summit and 5 State of Ohio, have invented new and useful Improvements in Paper-Hanging Machines, of which the following is a specification.

This invention comprehends the provision 10 of a wall papering machine, wherein a roll of paper is supported and unwound therefrom as it is applied to the wall, by moving the machine over the surface to be papered, means being provided for pasting 15 one side of the paper before it leaves the machine, and subsequently cutting off from the roll a strip of any desired length.

In carrying out the invention I also provide means for cutting off the selvage or 20 edge of the paper before it leaves the machine, and automatically roll the selvage upon another roller arranged therein.

The nature and advantages of the invention will be better understood when the following detailed description is read in connection with the accompanying drawings, the invention residing in the construction, combination and arrangement of parts as 25 claimed.

30 In the drawings forming part of this application, like numerals of reference indicate similar parts in the several views, and wherein:

Figure 1 is a side elevation of the machine 35 showing how the invention is used.

Figure 2 is a vertical sectional view there- 40 through, also showing the invention in use.

Figure 3 is a view taken at a right angle to Figure 1.

45 Figure 4 is a top plan view.

Figure 5 is a sectional view showing how the roller for the roll of paper is removed from the machine.

The machine forming the subject matter 50 of this invention comprises a casing indicated at 10, and which casing may be constructed from any suitable material, and vary in size and shape without departing from the inventive idea. The casing is provided with a handle or hand grip 11 by means of which the said casing can be moved over a wall or ceiling for the purpose above stated. Arranged within the casing 55 10 is a roller 12 which is mounted between the ends of the casing in the manner clearly illustrated in Figure 5, so that said roller

can be conveniently and easily removed. The roller 12 is provided with openings 13 in the opposite ends thereof and adapted to receive pins 14 carried by springs 15, as 60 shown. These springs can be easily flexed to separate the pins 14 from the roller 12 when it is desired to remove the latter from the casing. The roller 12 is adapted to support a roll of wall paper or the like indicated at 16, the paper when unrolled passing over rollers 17 and 18, and thence under a roller 19 and then out through the open side of the casing, over the roller 20 arranged in juxtaposition with the roller 19, as shown in Figure 2. As hereinabove 65 stated, the paper is applied to the wall or ceiling as it is unwound from the roll 16, this being accomplished by the roller 21 journaled at the top of the casing 10 and 70 projecting a slight distance beyond the open side thereof.

Arranged centrally within the casing 10 is a cylinder 22 adapted to contain paste or the like, the latter being introduced into 80 the cylinder in a suitable receptacle 23 through a filling tube or spout 24. Journaled within this cylinder is a brush, the body of which is indicated at 25, while the bristles are indicated at 26, and when this brush is rotated it applies the paste along 85 one side of the strip of paper passing about the rollers above described. For this purpose it will be noted in Figure 2 that the roller 19 rotates within an opening formed 90 in the cylinder 22, so that as the strip of paper passes beneath the roller 19 it is partly projected within the cylinder to receive the paste from the brush 25. While the brush may be rotated in any suitable 95 manner, this is preferably accomplished by means of a friction wheel 27 which contacts the brush to rotate the latter, incident to the rotation of the wheel 27 by being moved along the wall or surface to be papered.

100 After a strip of paper has been applied to the wall or ceiling, it is necessary to cut the paper from the roll at a point immediately adjacent the roller 21, and for this purpose I employ a knife blade 28 which 105 is operated by means of a handle 29, the handle being supported by spaced parallel bars 30, about each of which is arranged a coiled spring 31. These springs operate to normally hold the knife 28 in an 110 inactive position, and when it is desired to cut off the strip of paper it is only necessary

to push the blade outwardly against the tension of the springs 21.

It is frequently desirable and necessary to cut the paper longitudinally, especially to remove the selvage or edge from the paper, and for this purpose I employ a knife disk 32 arranged to cooperate with the roller 18 above referred to. The disk may be moved into or out of operative association with the roller 18, and when in position for use, it cuts the strip of paper longitudinally as the latter passes over the roller 18, as clearly illustrated in Figures 1 and 2 of the drawings. The paper cut from the strip is passed around a roller 34 which is rotated from the roller 19 by means of an idler 35, thereby simultaneously winding the cut portion of the paper about the roller 34, while the main portion or body of the strip of paper is being fed from the machine and applied to the wall or ceiling. The invention is very simple in construction and can be very conveniently and easily handled to accomplish the desired results.

While it is believed that from the foregoing description the nature and advantages of the invention will be readily apparent, I desire to have it understood that I do not limit myself to what is herein shown and described, and that such changes may be made when desired as fall within the scope of what is claimed.

Having thus described the invention, what is claimed as new, is:—

1. A wall papering machine comprising

a casing, a roller journaled therein and supporting a roll of wall paper; a roller mounted for rotation adjacent one end of the casing and projecting therefrom for applying paper to the wall as it leaves the casing, a plurality of guide rollers over which said paper passes, means for supplying one side of the paper with paste as it passes over said guide rollers, said means including a rotatable brush, a friction wheel for rotating said brush, and means for cutting a strip of paper from the roll at a point exterior of the casing.

2. A wall papering machine of the character described, comprising a casing, a roller journaled therein and supporting a roll of wall paper, a roller mounted for rotation adjacent one end of the casing and partly projecting therefrom for applying the paper to the wall surface, a plurality of guide rollers over which the paper passes, means for applying paste to one side of the paper as it passes over the guide rollers, said casing having a slot, a cutting disk mounted for movement in said slot toward and away from one of the guide rollers and cooperating therewith to cut the paper longitudinally as it passes through the machine, means for cutting a strip of paper from the roll at a point exteriorly of the casing, and means including a roller for winding the cut portion of the paper about said roller as it is cut from the strip longitudinally.

In testimony whereof I affix my signature.

STEVE BOROS.
